CLAIM

The ornamental design for a bottle topper, as shown and described.

DESCRIPTION

FIG. 1 is a perspective view of the bottle topper according to our new design;

FIG. 2 is a side elevational view thereof;

FIG. 3 is a side elevational view thereof;

FIG. 4 is a side elevational view thereof;

FIG. 5 is a side elevational view thereof;

FIG. 6 is a top plan view thereof; and,

FIG. 7 is a bottom plan view thereof.

The broken lines that form a cork shape at the bottom of the bottle topper, the top rim and bottom rim, and the words at the bottom and do not form any part of the claimed design.
